Des. 238,110
Patented Dec. 16, 1975

238,110

HOLDER FOR MAGNETIC TAPE CASSETTES

Richard Shyers, 737 Evergreen Parkway,
Union, N.J. 07083

Filed Nov. 12, 1973, Ser. No. 414,703

Term of patent 14 years

Int. Cl. D3—99

U.S. Cl. D87—1 D

FIG. 1 is a perspective view of a holder for magnetic tape cassettes showing my new design;

FIG. 2 is a bottom plan view; and

FIG. 3 is a sectional view taken along the line 3—3 of FIG. 1.

I claim:

The ornamental design of a holder for magnetic tape cassettes, as shown.
